GEORGE M. CHENEY AND LEON C. HARWOOD, OF SOUTHBIDGE, MASSACHUSETTS,
ASSIGNORS TO LITCHFIELD SHUTTLE COMPANY, OF SOUTHBIDGE, MASSA-
CHUSETTS, A CORPORATION OF MASSACHUSETTS.

THREAD-EYE FOR SHUTTLES.

1,337,389.

Specification of Letters Patent.

Patented Apr. 20, 1920.

Application filed August 31, 1915. Serial No. 48,316.

To all whom it may concern:

Be it known that we, GEORGE M. CHENEY, a citizen of the United States, and resident of Southbridge, county of Worcester, State 5 of Massachusetts, and LEON C. HARWOOD, a citizen of the United States, and resident of Southbridge, county of Worcester, State of Massachusetts, have invented an Improvement in Thread-Eyes for Shuttles, of which 10 the following description, in connection with the accompanying drawing, is a specification, like characters on the drawing representing like parts.

This invention relates to improvements in 15 thread eyes for hand threading or automatic loom shuttles and one of the objects thereof is to provide a thread eye which may easily be inserted in the eye hole, combined with means for retaining it in the eye and also 20 providing a barrier across the slot in the thread eye to prevent the filling from escaping from the eye once introduced therein.

Another object of the invention is to provide for hand threading shuttles a thread 25 eye of the character above described comprising a thread guiding member of vitreous material such as porcelain, glass or the like which will not be cut by the running of the thread.

Another object of the invention is to provide means for inclosing the vitreous thread 30 guiding member in a protecting sheath whereby the said member will be protected from injury during the operation of the 35 shuttle in the loom.

Other objects of the invention will more fully appear from the following description, the accompanying drawings, and will be pointed out in the annexed claims.

The drawing illustrates several species 40 of our invention, in which Figure 1 is a plan view of the end of a shuttle equipped with one of our improved thread eyes,

Fig. 2 is a side view of the same,

Fig. 3 is a vertical sectional view on lines 45 3—3 Fig. 1,

Fig. 4 is a similar vertical sectional view of a shuttle showing a different specific form of thread eye,

Fig. 5 is a similar view of another species 50 of thread eye which comprises a solid extension anchored in the shuttle by a pin,

Fig. 6 is a similar view of another modi-

fied form of thread eye formed of sheet metal and anchored in place by a pin en- 55 gaging an extended end of the thread eye.

Fig. 7 is a detail perspective view of the thread eye illustrated in Figs. 1, 2, 3,

Fig. 8 is a perspective view of the thread eye shown in Fig. 4, 60

Fig. 9 is a perspective view of the thread eye shown in Fig. 5,

Fig. 10 is a perspective view of the thread eye shown in Fig. 6,

Fig. 11 is a perspective view of another 65 form of thread eye involving our invention.

The thread eyes which are illustrated in the drawing are particularly adapted to be applied to the eye of a shuttle having communicating downwardly extending and substantially horizontal threading slots leading to the eye at or beneath the horizontal plane of the axis thereof, the eye being so located in the shuttle that the slot therein is at the bottom of the thread eye so that the thread 70 when introduced through the threading slots will pass into the eye through the bottom slot. When the thread is thus introduced into the thread eye the likelihood of the shuttle becoming unthreaded in its 75 flight to and fro in the loom is minimized, and this possibility is wholly prevented in the present invention by the provision of a barrier preferably in the form of a staple crossing the outer end of the thread eye 80 above the plane of the bottom thereof. This barrier preferably is made to engage the end of the thread eye in such a manner as to aid in retaining the eye in place in the shuttle, being spaced apart from one portion of 85 the wall thereof sufficiently to permit the introduction of the thread.

These essential features it will be noted are common to all of the species of thread eye illustrated in the accompanying drawing.

In the preferred embodiments of the invention disclosed herein the shuttle body 1 may be of the usual type provided with a bobbin or cop chamber 2 communicating 100 through the throat 3 with a threading aperture or well 4 from which leads a downwardly extending threading slot or kerf 5 which connects with a substantially horizontal kerf 6 lying preferably in substantially 105 the horizontal axial plane of the shut-

tle body. The horizontal kerf 6 communicates with the usual eye hole 10 at or beneath the horizontal plane of its axis.

In hand threading and automatic shuttles the shuttle eye is usually provided with a metallic bushing to prevent the thread from wearing into and cutting the wall of the shuttle eye. Such metallic members are however found to be ineffective on certain kinds of yarn, particularly upon silks as they are liable to be cut by the running thread. We have therefore provided a thread eye of vitreous material such as porcelain or glass or the like, having a smooth thread engaging surface.

We are aware that vitreous eyes have been used in connection with shuttles heretofore made but such eyes have ordinarily been constructed of porcelain and like fragile material which when made in slotted form for use in hand threading shuttles is readily crushed by the bending of the beak 8 of the shuttle, which is between the kerfs 5 and 6, when the shuttle enters the box at the end 25 of the lay. We have discovered that this may be avoided by the use of a thread eye of specially tempered glass or by inclosing the tempered glass or other vitreous thread guiding member of the thread eye within 30 a protecting shell and by providing a barrier at the outer end of the thread eye which engages the end wall of the thread eye or of the metallic protecting shell and also of the end of the inclosed vitreous member at 35 the rear of the slot and forces the inner end of the thread eye firmly against a shoulder formed in the body of the shuttle as will hereinafter be more fully described.

As illustrated in Figs. 1 to 3 inclusive 40 the thread eye 10 is of a substantially cylindrical form slotted at its bottom and having a downwardly extending tangential portion 11 seated in a slot 12 in the body of the shuttle. This thread eye may be constructed 45 of any suitable material but preferably is of tempered glass of the character above described. The edges of the thread eye are slightly convergent as shown in Fig. 3, so that the straight portion 11 is of a greater 50 length than the forward curved portion 13 of the eye. When the thread eye is assembled in the shuttle the inner end wall 14 of the thread eye is caused to abut against a shoulder 15 in the body portion of the shuttle, the outer end wall 16 of the extended portion being located in a plane substantially tangential to the curved surface 17 of the thread groove in the side of the shuttle. The thread eye 10 is preferably secured 55 in place by a barrier or staple 18 which is driven into the wood of the shuttle in such a manner as to engage the outer end wall 16 of the thread eye and force the opposite wall 14 of the thread eye against the shoul-

der 15. Inasmuch as the curved outer wall 65 of the thread eye is slightly inclined a space 19 will be provided between it and the barrier 18 which will permit the introduction of the thread into the thread eye.

Figs. 4 and 8 show a modified form of 70 thread eye which comprises a central cylindrical thread guiding member 20 preferably of vitreous material, such as tempered glass of the character above described, inclosed within a rigid protecting casing 21, preferably of metal such as steel and secured therein by a lining or a coating 22 of cement or like adhesive material. This thread eye like the other is provided with a longitudinal bottom slot 24 the outer end of the 80 thread eye being beveled or curved as it approaches the slot to form a passage 25 adapted to permit the introduction of the thread. The inner wall 26 of the thread eye in this construction is caused to abut against 85 a shouldered portion 27 of the shuttle body and the thread eye is retained in its place in the shuttle by a staple 28 embedded in the wood of the shuttle and engaging the outer wall 29 of the thread eye at the rear 90 of the longitudinal slot in the same manner as illustrated in Figs. 1, 2, and 3. In this construction the staple also overlies and preferably engages the end wall of the vitreous lining member and thereby serves to 95 prevent the latter from being discharged from the shuttle eye if for any reason it becomes loose within the protecting casing.

In Figs. 5 and 9 a different specific form of thread eye is disclosed. This thread eye 100 comprises a slotted cylindrical thread guiding member 30 of vitreous material inclosed within a metallic protecting sheath 31. In this particular form the protecting sheath is constructed from a cylindrical steel rod 105 which is bored axially through a portion of its length to receive the thread guiding member and is provided with a transverse slot 32 to communicate with the inner open end 110 of the thread guiding member 30. In assembling this eye in the shuttle the eye hole 34 is extended through the shuttle, the cylindrical thread eye above described is then positioned and introduced so that the longitudinal slot will be located at the bottom 115 of the thread eye; the thread eye is secured in place by a pin 35 passing through the wood of the shuttle and the end 33 of the metallic member. A staple 36 embedded in the wood of the shuttle at the outer end 120 of the thread eye serves to prevent the thread from being thrown out of the eye.

In Figs. 6 and 10 a still further modification of the invention is illustrated. In this case the thread eye comprises a sheet metal cylinder 37 having a longitudinal bottom slot 38 and a lateral slot 39 to receive the thread and permit the same to be introduced

into the chamber 40 of the thread eye, the cylindrical portion 37 being provided with a cylindrical extension 41 adapted to receive a securing pin.

5 As illustrated in Fig. 6 the aperture 42 which forms the eye hole is extended through the wall of the shuttle, the thread eye is introduced therein and is retained in place by a pin 43 passing downwardly through the 10 body of the shuttle into the wall of the shuttle eye. At the outer end the staple 44 is embedded in the wood of the shuttle and crossing the slot 38 serves to prevent the escape of the thread from the shuttle.

15 It will be understood that in securing the thread eyes illustrated in Figs. 5, 6, 9, and 10 in the shuttle they are first positioned properly within the shuttle and a drill forced from the top of the shuttle 20 through the wood of the shuttle and the metal of the thread eye, the drill is then removed and the pin inserted.

25 In order to assist in positioning the thread eye a recess or key-way 45 (see Figs. 6 and 10) may be provided at the end of the thread eye extension. By the use of the proper tool, such as a jig, to engage this key-way the thread eye may be retained in proper position while being inserted in the 30 eye hole.

Fig. 11 illustrates another embodiment of this invention which includes the form of thread eye illustrated in Fig. 10 with the downwardly extending flange illustrated in 35 Figs. 2 and 3. This form of thread eye comprises a cylindrical portion 46 which preferably incloses a vitreous thread guiding member 47 the cylindrical portion and the inclosed vitreous thread guiding member having a longitudinal bottom slot 48 and a transverse slot 52. The rear wall of the cylindrical portion 46 is extended substantially tangentially to form a downwardly projecting extension 49 adapted 45 to engage a suitable slot in the wall of the shuttle at the bottom of the eye hole as illustrated in Fig. 2, the inner end of said flange abutting against a shoulder in the shuttle body and the outer end being engaged by a staple as in Figs. 2 and 3 as heretofore described.

The inner end 50 of the metallic thread eye may if desired be provided with a key-way 51 to aid in positioning the thread eye 55 in the shuttle in the manner above described. However, the key way is not ordinarily necessary in this form of thread eye, since the thread eye is properly positioned by the downwardly extending flange 49. The cylindrical portion is provided with a lateral slot 52 through which thread may be led 60 to the thread guiding portion of the eye. This form of thread eye may be used with

or without the vitreous lining as will be readily apparent to those skilled in the art.

In the forms of thread eye illustrated in 65 Fig. 11 felt or wool may be readily introduced through the open extended end of the thread eyes to produce the desired amount of friction upon the running thread.

It will be understood that the disclosure 70 is merely illustrative of some of the embodiments of our invention but is not restrictive and that the same may be embodied in other forms within the meaning and scope of the following claims.

Having thus described our invention what we claim as new and desire to secure by Letters Patent is:

1. A loom shuttle having an eye hole, a slot to provide a thread passage thereto, the end wall of said eye hole presenting a shoulder, a thread eye in said eye hole provided with a longitudinal bottom slot, and a staple engaging a portion of the end wall of the thread eye and forcing the opposite end 80 of said eye against said shoulder, said staple overlying the bottom of the slot, whereby the thread eye is secured in the eye hole and the thread prevented from escaping from the eye when once introduced therein. 90

2. A loom shuttle apertured to form an eye hole and slotted to provide a thread passage thereto, a thread eye located within said eye hole having a hollow vitreous thread engaging member and an inclosing 95 casing provided with registering longitudinal bottom slots communicating with said threading slots, a staple engaging a portion of the outer wall of the thread eye and lining member at the rear of said slot to secure the same in the eye hole and spaced apart from said wall upon the opposite side of said slot whereby the thread may be introduced readily through the guiding slot in the thread eye but will be prevented from 100 escaping therefrom.

3. A loom shuttle having an aperture forming an eye hole and slotted to provide a passage thereto, a thread eye located in said eye hole comprising a metallic cylindrical bushing having a lining of vitreous material secured therein, the metallic member and vitreous lining member being provided with registering longitudinal bottom slots connecting with the threading 115 slot in the shuttle, means for securing the thread eye in the eye hole, including a staple engaging a portion of the end wall of the eye upon one side of the slot and spaced apart from said wall upon the opposite side 120 of the said slot.

In testimony whereof, we have signed our names to this specification.

GEORGE M. CHENEY.
LEON C. HARWOOD.
